Primary Examiner — Omeed Agilee*(74) Attorney, Agent, or Firm* — McCoy Russell LLP(57) **CLAIM**

The ornamental design for a sensor with connector, as shown and described.

DESCRIPTION

FIG. 1 is a rear top perspective view of a sensor with connector according to the claimed design.

FIG. 2 is a front view of the sensor with connector.

FIG. 3 is a rear view of the sensor with connector.

FIG. 4 is a right side view of the sensor with connector.

FIG. 5 is a left side view of the sensor with connector.

FIG. 6 is a top view of the sensor with connector.

FIG. 7 is a bottom view of the sensor with connector.

FIG. 8 is a perspective view of the sensor with connector with the sensor and connector in a detached configuration.

FIG. 9 is a bottom perspective view of the sensor with connector with the connector removed to show details not otherwise discernable from the drawings; and,

FIG. 10 is a front view of the sensor with connector shown in FIG. 9.

The broken lines in the drawings illustrate portions of the sensor with connector that form no part of the claimed design.
